DESIGN FOR A BOY'S SUIT

David T. Kogan, New York, N. Y.

Application September 8, 1944, Serial No. 115,219

Term of patent 14 years

(Cl. D3—17)

To all whom it may concern:

Be it known that I, David T. Kogan, a citizen of the United States, residing in New York city, in the county of New York and State of New York, having invented a new, original, and ornamental Design for a Boy's Suit, of which the following is a specification, reference being had to the accompanying drawing, forming part thereof.

Fig. 1 is a front view of a boy's suit showing my design,

Fig. 2 is the rear view of the suit shown in Fig. 1, and

Fig. 3 is a front view of the suit shown in Fig. 1 in opened position.

The characteristic feature of my design resides in the combination on a one piece boy's suit of the type disclosed, of the trouser seams which extend onto the front and have pockets concealed therein, said suit having a full length front opening terminating in the trouser fly, all as shown.

I claim:

The ornamental design for a boy's suit, substantially as shown and described.

DAVID T. KOGAN.
